UNITED STATES PATENT OFFICE

ANTON BROSCH, OF VIENNA, AUSTRIA

APPARATUS FOR SUBMERGED INTESTINAL LAVAGE

Application filed December 18, 1928, Serial No. 326,752, and in Germany December 24, 1927.

This invention relates to apparatus for submerged intestinal lavage and it has for its object to provide apparatus for the purpose specified adapted to be fixed in position in a few moments in or on any of the usual types of domestic bath, and to be removable with equal ease, so that the bath can again be put immediately to its ordinary use.

Apparatus according to this invention 10 consists essentially of three elastic straps, cords, spiral springs or the like, fixed in a suitable manner on the edges of the bath and stretched across it, the one nearest to the foot of the bath serving to retain a draining 15 pipe fitting into the waste of the bath, whilst the other two elastic cords carry the springing apparatus proper, which is held in a watertight manner against the patient's body by the tension of the elastic cords due 20 to his weight as he lets himself sink into the bath.

It has been found, that when the patient in the bath lifts his pelvis or lower abdomen, bearing with his back against the head 25 of the bath, the hindmost elastic cord remains taut, but the tension of the forward one, securing the laving bowl, relaxes to such an extent that the lavage water is liable to leak out into the bath.

30 It is therefore advisable, to use in substitution for the forward elastic cord supporting the laving bowl a non-elastic thong, chain, or the like which can be kept permanently taut by attaching a suitable weight. The 35 thong or the like can have one of its ends secured to the edge of the bath in such a way as to be displaceable longitudinally along the bath, the other end running free over the 40 opposite edge of the bath and carrying the requisite weight, or else a weight may be attached to both ends of the cord, in which case the latter runs freely over bath edges of the bath and the two weights will serve 45 to maintain the required tension.

The hindmost elastic supporting cord for the laving bowl can also be dispensed with, the supporting ring for the laving bowl being in that case connected by an elastic link 50 to a hook-shaped shoe or other appliance

which hooks direct on to the edge of the bath at its head.

The drawings show one example of the subject matter of the invention. Figs. 1 and 2 show one form of execution of an appliance 55 attached to a bath, being respectively a side view with the bath in longitudinal section, and a partial view from above. Figs. 3 and 6 show respectively a plan view and a front view (partially in section) of two variations 60 in the supporting device for the laving bowl; Fig. 7 shows details, Figs. 8 and 9 two modified forms of the draining device, Figs. 10 and 11 the lavage apparatus proper in two different forms, Fig. 12 a frame for immersion in the bath where the latter is completely bordered with tiles, and Fig. 13, the footrest.

In Figs. 1 and 2, two elastic rubber thongs, straps, or spiral springs 3, 3₁ or the like are 70 shown placed across the bath and secured to the edges 1 of the bath by means of hook-shaped shoes 2 near the head of the bath, and readily removable at will; there is a third elastic cord 3₂ at the foot of the bath. It is advisable that the cords or springs 3, 3₁, 3₂, should have a protective covering of rubber or some elastic metal sheathing so that in the event of the breaking of a spring or rubber thong it shall not hurt the patient as it 75 snaps back. The two forward cords 3, 3₁, carry the supporting appliance for the lav- 80 ing apparatus or intestinal syringe. This ap- 85 paratus consists of a central part 4 which may be either a ring, frame or loop, preferably of some resilient material, into which the actual syringing apparatus 5 is inserted. The sup- 90 porting ring 4 is connected on one side to two elastic thongs or springs 7 also sheathed in rubber the opposite ends of which are 95 secured to a hook-shaped shoe 8 which is ad- 100 justed to hook on to the central elastic cord 3₁ placed across the bath. The reason why the tension springs 7 are divided into two is to make room for the patient's privy parts and to obviate uncomfortable pressure. The supporting ring 4 is held by a flexible metal band 9 or girdle or such like which will ad- just itself in close contact to the patient's body, and this is secured by a hook 10 to

the cross-cord 3 placed nearest to the head of the bath. The patient sits upon the laving bowl and bears it down by his weight on to the bottom of the bath. This increases the tension of the supporting cords, so that the laving bowl is held in a watertight manner against the patient's seat.

As previously stated at the outset, it may be thought preferable, in order to secure a better watertight fit, to have the supporting cords arranged in a different manner, as shown in Figs. 3, 4 and 5, 6. Instead of the forward elastic supporting cord 3₁, the middle one of the three shown in Figs. 1 and 2, a non-elastic thong or chain or suchlike 3₁^a may be used. This is shown in Figs. 3 and 4 with one end secured to a shoe 2 that can be slid longitudinally along the edge of the bath, its other end being freely suspended over the opposite edge of the bath and carrying a weight of 3 to 5 kgs. and designed to keep the cord 3₁^a permanently taut. By means of the shoe 8, the ring 4 supporting the laving bowl 5 is hooked on to this cord. The hindmost elastic supporting cord 3 is in this case not secured to the lateral edges of the bath, but to the curved head of the bath by means of shoes 2.

In Figs. 5 and 6 the non-elastic supporting cord, chain 3₁^a or suchlike carries at each end a weight 11 of 3 to 5 kgs. The cord is laid loosely over the two opposite edges of the bath, or else runs over two shoes 2₁ placed on the edges of the bath, and capable of being slid into the desired position and carrying forks to guide the cord, the latter being kept taut by means of the weights. The hindmost cord 3 shown in Figs. 1 and 2 is in this case omitted and the flexible metal band 9, girdle, or suchlike connected to the supporting ring of the laving bowl is hooked to the top edge of the bath by means of a shoe 10, and an elastic connecting link 91.

Fig. 7 shows some further alternative forms of the shoes 2₁ to carry the cord 3₁^a, weighted at both ends. The shoe can have, instead of the fork 2₁', a roller 2₁''', or a ring or sleeve 2₁'''.

The intestinal syringe (Fig. 10) consists of two parts, viz. a hollow framework 5, of rigid material, to fit the patient's seat, provided with a catheter tube 12 to admit the lavage water and carrying the movable rectal nozzle 13. The lower part of the framework has a padded edge 14 projecting outwards over which the second part of the laving apparatus, a thick soft rubber cup 15, with an inward projecting ring beading 16 is adjusted. The laving apparatus is made in two parts for the greater ease both of construction and cleaning. The rubber cup 15 ends in a tube 17 which connects with the draining appliance. Alternatively the framework 5 with its projecting edge 14 can be arranged to fit into an aperture fashioned

after the manner of a buttonhole in a rubber tube of suitable width.

As the faeces will float on or near the top of the lavage water and will therefore glide along the upper part of the walls of the laving bowl, accumulations of faeces are liable to form on account of the corners and recesses within the lavage bowl and the further circumstance that the inlet pipe crosses the draining passage, and the laving bowl may get choked up in consequence.

This objection is overcome by the form of laving bowl shown in Fig. 11. This consists of a hollow piece 5^a made of a suitable rigid, semi-rigid or resilient material, on the front of which is the draining connection 18 placed close up to the watertight fitting lip 5₁^a, so that the draining passage has a smooth upper surface free from corners or niches and the stream of faeces is able to flow freely along it without obstruction or hindrance. The connection 19 for the inlet pipe 12 forms the continuation of the bottom lining of the laving bowl 5^a, the inlet pipe itself lying near the bottom of the vessel so that it does not cross the path of the draining stream. The pipe 12 is adjustable by sliding within the connection 19.

The laving bowl 5^a in its lower and rearward part has an outer surface mainly spherical in shape, and as it is this part that comes into contact with the bottom of the bath it follows that the actual position in which it rests on the bottom of the bath can be varied indefinitely, which also helps to obviate stoppage through accumulations of faeces. A tube leading to the draining appliance, is slid over the drain connection 18.

The draining appliance (Figs. 1, 8 and 9) consists of a pipe 20 rising above the edges of the bath, carrying at the top a rotatable cap 21 with a forked shoe 22, to receive the cord 3₂ secured to the edges of the bath, which has previously been mentioned. The lower extremity of the pipe 20 fits loosely into the bath waste 24, a packing washer 23, preferably made of rubber sponge being interposed, and the cord 3₂ holds the pipe down to make a watertight fit. The pipe 20 has a lateral connection 25 into which a glass elbow 26 is fitted, and on to this is slid the tube 17 which carries the contents of the patient's bowel away from the laving bowl. Fig. 8 shows that the drain pipe 20 has orifices 27 in its lower part, and above the undermost row of these a coarse-meshed sieve 28 is placed across. The perforated part of the pipe 20 is surrounded by a hollow cylinder 29 closed at the top, the lower edge of this bearing against the washer 23 as it lies on the bottom of the bath. The sieve 28 retains the bigger lumps of faeces carried out with the lavage water. The subsequent flow of water breaks these up and carries them, together

with the smaller particles of faeces above the sieve through the aperture 27 into the hollow cylinder 29 and thence below the sieve through the lower orifices 27 into the waste pipe.

In Fig. 9 the pipe 20 is shown with an inner pipe 20¹ of smaller diameter with orifices 27 and a cross-sieve 28; this works in the same way as just described.

10 If the lavage operation has to be carried out for instance in a bath that is tiled in, then the elastic cords 3, 3₁, 3₂ to be stretched across the bath must be secured to the lengthwise members of a frame (Fig. 12) inserted in the 15 bath. This consists of a headpiece 30 resting on the head of the bath carrying two rods 31 disposed lengthwise of the bath, having downwardly directed elbows and ending in a stirrup-shaped footpiece 32 which comes to 20 rest on the bottom of the bath. The elastic cords are secured to the longitudinal members 31 of the frame. In place of the footpiece 32 the frame can be made with a second head, so that the whole appliance rests on the 25 edges of the bath. It is also possible for the cords to be attached to a frame or framework so made that its longitudinal parts rest outside the lateral edges of the bath altogether.

A further part of the appliance according 30 to this invention consists of a ladderlike device 33 designed to serve as footrest (Figs. 1 and 13) and made of wood or other suitable material, the side members being extended in the direction of the head of the bath well beyond the rungs to a length of about half the 35 total length of the ladder, i. e. so that the rungs are all within that half of the ladder that points to the foot of the bath. The purpose of this is to overcome the tendency which 40 the ladder would otherwise have to slide up at the foot of the bath when the patient bears with his feet against the rungs. By thus lengthening the side members of the device at the fulcrum of the ladder, when the patient 45 exerts pressure against it with his feet, is displaced so far from the point of pressure that the ladder is held down.

Claims:

1. An appliance for intestinal lavage under 50 water that can be fitted to an ordinary bath comprising three elastic cords adapted to be fixed in a suitable manner on the edges of the bath and stretched thereacross, said cords being sheathed in flexible metal tubes, and one 55 of them being adapted to be placed near the foot of the bath to hold down a drain pipe fitting loosely into the waste of the bath, and the other two cords adapted to support the lavage bowl and hold it watertight against 60 the seat of the patient due to the tension created by his weight as he sinks into the bath.

2. A device according to claim 1, in which 65 the supporting device for the lavage bowl consists of a ring to surround the latter, said ring being hooked on one side, by means of

two extensible straps placed at a sufficient width apart to accommodate the privy parts of the patient without pressure, to the appropriate cord while the ring, is also secured to the other cord.

3. A device according to claim 1, in which the elastic cords are attached to longitudinal members of a frame associated with the bath, from which they can be easily removed.

4. A device according to claim 1, in which the drain pipe has its lower part surrounded by a hollow cylinder closed at the top and perforated with a number of apertures of varying heights, between which a coarse-meshed cross-sieve is inserted across the pipe.

5. A device according to claim 1, in which the drain pipe has a smaller pipe with perforations and a flat sieve inserted therewithin and standing clear of its inner surface.

6. An appliance for intestinal lavage under water adapted to be fitted to an ordinary bath, comprising a laving bowl of which the discharge connection placed at the forward end and in immediate contact with the forward part of the watertight lip of the laving bowl, so that its inner surface is smooth and unbroken, while the inlet pipe is inserted in the lower part of the laving bowl and lies along the bottom thereof.

7. A device according to claim 6, in which the lower and rearward part of the laving bowl presents a spherical-shaped outer surface without projections.

8. A device according to claim 1, in which a ladder is made of a rigid material lying on the bottom of the bath and is provided to serve as a rest for the feet of the patient, its uprights being extended towards the head of the bath so far beyond the rungs that approximately only the half of the ladder pointing towards the foot of the bath carries any rungs.

9. An appliance for intestinal lavage under water that can be fitted to an ordinary bath, comprising three cords adapted to be fixed in a suitable manner on the edges of the bath and stretched thereacross, said cords being sheathed in flexible metal tubes, and one of them being adapted to be placed near the foot of the bath to hold down a drain pipe fitting loosely into the waste of the bath, and the other two cords adapted to support the lavage bowl and hold it watertight against the seat of the patient due to the tension created by his weight as he sinks into the bath, the central cord being of a non-elastic material which has one end secured to the edge of the bath by a longitudinally displaceable shoe and the other end hanging free over the opposite edge of the bath and carrying a weight which maintains it constantly taut.

10. An appliance for intestinal lavage under water that can be fitted to an ordinary bath, comprising three cords adapted to be

fixed in a suitable manner on the edges of the bath and stretched thereacross, said cords being sheathed in flexible metal tubes, and one of them being adapted to be placed near the foot of the bath to hold down a drain pipe fitting loosely into the waste of the bath, and the other two cords adapted to support the laving bowl and hold it watertight against the seat of the patient due to the tension created by his weight as he sinks into the bath, the central cord being of a non-elastic material which has a weight at each end so that the central cord can be loosely thrown over both edges of the bath.

15 11. A device according to claim 1, in which the supporting device for the laving bowl consists of a ring to surround the latter, said ring being hooked on one side by means of two extensible straps placed at a sufficient width apart to accommodate the privy parts of the patient without pressure to the appropriate cord, while the ring is also secured to the head of the bath by a belt.

25 12. An appliance for intestinal lavage under water adapted to be fitted to an ordinary bath, comprising a pipe extending above the bath and fitted loosely into the waste of the bath to carry off the lavage water, a packing washer of rubber sponge 30 interposed between the waste and the pipe, and a rotatable cap at its upper extremity provided with a fork to accommodate a holding-down cord and having a lateral connection for the excreta-tube.

35 13. An appliance for intestinal lavage under water adapted to be fitted to an ordinary bath, comprising a laving bowl consisting of a framework made of a rigid substance and carrying a laving nozzle, having its upper surface made to fit the seat of the patient and its lower edge projecting outwardly, and a rubber hood connected to the excreta-tube.

45 14. An appliance for intestinal lavage under water adapted to be fitted to an ordinary bath, comprising a laving bowl consisting of a framework of a rigid substance and carrying a laving nozzle, having its upper surface made to fit the seat of the patient and its lower edge projecting outwardly, and a rubber hood connected to a rubber excreta-tube with a slit in the form of a buttonhole being arranged to fit over the projecting edge.

55 In testimony whereof I have hereunto set my hand.

Dr. ANTON BROSCHE.
